UNITED STATES PATENT OFFICE.

ADOLPH W. LISSAUER, OF NEW YORK, N. Y.

NOZZLE.

1,223,081.

Specification of Letters Patent. Patented Apr. 17, 1917.

Application filed April 1, 1916. Serial No. 88,274.

To all whom it may concern:

Be it known that I, ADOLPH W. LISSAUER, a citizen of the United States, and a resident of the city of New York, borough of Manhattan, in the county and State of New York, have invented a new and Improved Nozzle, of which the following is a full, clear, and exact description.

My invention relates to nozzles for generating a spray of liquid in a finely divided state. It constitutes an improvement on the structure disclosed in my pending application filed January 27, 1916, the serial number of which is 74,681. The object of the invention is to provide a simple and inexpensive nozzle which will offer the least resistance to flow therethrough, which will not clog, which can be easily cleaned during the operation, and with which a maximum amount of liquid can be delivered with a minimum of initial pressure.

With the above and other objects in view, the nature of which will more fully appear as the description proceeds, the invention consists in the novel construction, combination and arrangement of parts as herein fully described, illustrated and claimed. In the accompanying drawings, forming part of the application, similar characters of reference indicate corresponding parts in all the views.

Figure 1 is an elevation of an embodiment of my invention;

Fig. 2 is a vertical section through the housing of the nozzle, the distributor being shown in elevation;

Fig. 3 is a section of the distributor, the tip being shown in elevation disconnected from the distributor; and

Fig. 4 is a horizontal section on line 4—4, Fig. 3.

Referring to the drawings, the housing 6 of the nozzle is formed of a tubular portion 7 having at one end a polygonal base 8 to be engaged by a wrench. The other end of the tubular portion is provided with a tapering dome 9 terminating in a flared opening 10. The angle of the flare with the vertical is about 60°. The tubular portion 50 at the base has a shoulder 11 against which a threaded base collar 12 of a distributor 13 abuts when the distributor is screwed into the housing.

The base collar 12 of the distributor is 55 surmounted by a cylindrical portion 14 fitting snugly into the tubular portion of the

housing. The cylindrical portion 14 is dominated by a reduced cylindrical portion 15 which has a tapering part 16 at the top properly spaced from the tapering dome 9. 60 The base angle of the tapering part 16 is greater than the base angle of the tapering dome 9; consequently, the distance between the two tapers decreases as the outlet of the nozzle is approached.

The tapering part 16 of the distributor has an axially-threaded bore into which the stem 17 of a distributor 18 is screwed through the flared opening 10 of the dome. The deflector has a tapering curved surface 70 19 facing the flared opening 10. The tapering surface 19 opposite the flared opening is parallel therewith; but at the margin the angularity of the tapering surface 19 increases and is substantially 75 80° with the vertical. The size of the stem 17 is such that the area between the distributor and the housing is minimum at the inner edge of the opening 10. The larger diameter of the deflector is at least three 80 times the diameter of the opening 10 at the inner edge.

The distributor 13 has an axial bore 20 open at the base collar and thereat provided with a thread to receive the end of a pipe 85 21, which is to supply the liquid to be sprayed. The portion 22 above the end of the pipe 21 has a capacity such that the static pressure of the liquid is kept substantially constant. Two diametrically opposite 90 passages 23 extend from the portion 22 into the annular space formed within the housing 6 of the distributor. These two passages are in a plane at right angles to the axis of the nozzle.

Each passage enters the annular space formed by the housing 6 and the cylindrical portion 15 of the distributor below the high end of an inclined plane 24, each of said planes being formed on the cylindrical portion 14 and partly encircling the cylindrical portion 15 and forming an integral part therewith. The inclined planes are made as short as possible to eliminate friction and the tendency of the liquid moving thereupon to clog within the housing. The passages 23 are so formed in the distributor that they direct the liquid against the inner surface of the tubular portion 7 at as small an angle as possible, the object being to secure the 105 conversion from static to velocity pressure with the least frictional loss.

The liquid delivered through the passages 23 is given a rotary movement by the inner surface of the tubular portion 7. The two inclined planes inclosed in the annular space of the nozzle form therewith a double spiral the length of which is sufficient to impart proper advancing rotation to the liquid delivered from the passages 23. The rotation of the liquid continues as it advances to the deflector. The velocity of the liquid increases as it approaches the deflector, due to the reduction of area between the tapering dome 9 and the tapering portion 16.

15 The area of the space between the opening 10 and the deflector is less than the sum of the area of the impeller openings 23 in the distributor. At the maximum velocity the direction of flow is changed, and the 20 tendency of the rotating liquid is to form a hollow cone with sides of an angle of approximately 30° with the vertical. The sharp edge of the opening forces the discharged rotating liquid to follow the curved 25 taper of the deflector. The thickness of the sheet of rotating liquid as it follows the curved surface of the deflector becomes less, due to the increase of the diameter, and at the margin the sheet of liquid is thrown off 30 from the deflector in the form of finely divided particles, by the centrifugal force which brings up the fine sheet of water. In this way it is possible to obtain a finely divided spray, the same as when the orifice 35 spaces between the housing and distributor cone are infinitesimally small, but without the disadvantage of an abnormal tendency to clog and an abnormal resistance to flow. If the spaces between the deflector and the 40 opening 10 become clogged, the said space may be increased by partially unscrewing the deflector from the distributor to allow the rotating liquid to carry away the obstruction between said deflector and the 45 opening.

The force which keeps the liquid on the tapering surface of the deflector will make it follow the incline of its surface after it has been thrown off, and the angularity of 50 the spray leaving the deflector will be substantially that of the deflector at the margin, which is, as previously stated, about 80° from the vertical.

I claim:

55 1. The herein described nozzle, consisting of a housing having an internally threaded base and a cylindrical portion above the

base and terminating in a dome provided with a flaring opening, a distributor having an exteriorly threaded base and two cylindrical portions of different diameters, the smaller one of which has a tapering end provided with a threaded socket, the distributor having on the exterior of its cylindrical portions oppositely inclined surfaces and provided with a bore in two diameters opening at the base, and with openings leading from the smaller diameter of the bore out through the distributor below the high ends of the inclined surfaces thereof, the larger diameter of the bore being internally threaded, and a tapering deflector having a stem extending through the opening of the housing and provided with a threaded end screwing into the socket of the distributor.

2. The herein described nozzle, comprising a housing having a cylindrical portion terminating in a dome provided with a flaring opening, a distributor secured in the housing and having a tapering upper end provided with a threaded axial socket, the distributor having an axial bore in two diameters, and open at the base of the distributor, the distributor being provided with oppositely inclined surfaces on its exterior and with openings leading from the smaller portion of the bore out below the high end of the inclined surfaces, and a tapering deflector having a stem extending through the opening of the housing and provided with a threaded end engaging the socket of the distributor.

3. The nozzle herein described comprising a housing having a dome shaped top provided with an opening, a distributor secured in the housing and having an inclined upper end, an axial bore open at the base of the distributor, oppositely inclined surface on its exterior, and openings leading from the bore out through the distributor below the high end of the inclined surfaces, and a deflector having a stem extending through the opening of the housing and adjustably secured to the tapering end of the distributor.

In testimony whereof I have signed my name to this specification in the presence of two subscribing witnesses.

ADOLPH W. LISSAUER.
